UNITED STATES PATENT OFFICE.

JAMES J. DIMEO, OF CLEVELAND, OHIO, ASSIGNOR TO THE PERMOLD COMPANY, OF CLEVELAND, OHIO, A CORPORATION OF OHIO.

APPARATUS FOR MAKING CASTINGS.

Application filed September 11, 1926, Serial No. 134,895. Renewed September 6, 1928.

This invention relates to a method and apparatus for forming castings, particularly hollow cup shaped castings, of aluminum or an aluminum alloy.

5 An object of the invention is to provide a mold by which the casting is formed with its sprue upon the tubular skirt portion of the casting instead of upon the top portion thereof, so that the trimming and finishing of the 10 casting is facilitated particularly when the top is apertured or of otherwise irregular contour.

15 A further object is to form a casting with the excess metal in the form of a sprue or of a sprue and riser joined to the metal of the casting by straight narrow webs, so that the excess metal can be quickly and easily trimmed off.

20 A further object is to provide a permanent sectional mold in which the core members and outer mold sections can be quickly and easily separated to free a casting.

25 With the above and other objects in view, the invention may be said to comprise the apparatus as illustrated in the accompanying drawings hereinafter described and particularly set forth in the appended claims, together with such variations and modifications thereof as will be apparent to one skilled in 30 the art to which the invention appertains.

Reference should be had to the accompanying drawings forming a part of this specification in which:

35 Figure 1 is a top plan view of a mold embodying the invention showing the sections in closed position.

40 Fig. 2 is a front elevation of the mold showing the sections in open position and a casting in the position in which it has been formed in the mold.

Fig. 3 is a central vertical longitudinal section through the mold taken on the line indicated at 3—3 in Fig. 1.

45 Fig. 4 is a central vertical transverse section through the mold taken on the line indicated at 4—4 in Fig. 1.

Fig. 5 is a top plan view of a casting formed in the mold.

Fig. 6 is a side elevation of the casting.

50 Where a cup shaped casting is to be formed with one or more apertures in the top, the mold must be cored to provide the apertures in which case it is difficult, if not impossible, to provide a gate opening into the bottom forming portion of the mold cavity from

which the molten metal can be properly distributed throughout the mold cavity. Furthermore, the trimming of the sprue from the bottom of a casting which is apertured or otherwise irregular in contour is a more difficult and expensive operation.

60 The present invention provides a mold by which all the excess metal in the sprue and in the riser is joined to portions of the casting which are continuous and of regular contour, so that the casting can be easily and quickly trimmed. This result is accomplished by introducing the molten metal into the skirt forming portion of the mold cavity through a straight narrow elongated opening 65 or gate cavity, whereby the sprue is joined to the body of the casting by a straight narrow web. If a riser forming cavity is provided in the mold, this cavity also communicates with the skirt forming portion of the cavity 70 through a narrow opening or gate cavity, so that the riser also is connected to the body of the casting by a narrow web.

75 The casting is preferably formed in a mold which has the bottom forming portion uppermost and has a sprue cavity which extends well above the top of the casting cavity and which has a long narrow vertical gate opening into the substantially vertical skirt forming portion of the casting cavity which 80 extends from adjacent the upper end of the cavity toward the bottom. If a riser cavity is provided, it is preferably positioned diametrically opposite the gate and extends above the top of the casting cavity, the riser 85 cavity communicating with the casting cavity through a narrow opening or gate cavity adjacent the top thereof so that metal can be drawn from the riser cavity upon shrinkage 90 of the metal in cooling.

95 As shown in the accompanying drawings, the mold employed is preferably a permanent mold formed of metal and composed of a suitable core member and separable sections suitably recessed to fit around the core and form the casting sprue and riser cavities and also the gate cavities.

100 The mold is mounted upon a suitable bed or base member 1 which has a central aperture in which there is fixed a vertical sleeve 2, 105 in which is slidably mounted a core member 3 movable upwardly into molding position and in the upper end of which is mounted a central core pin 4 which projects above the upper end of the main core member 3 to co- 110

operate with sleeve 20 to form a central aperture in the casting. The core member 3 may also be provided at the top thereof with integral projections 5 which serve to form 5 additional apertures in the top portion of the casting between the center and periphery thereof. The core member 3 is preferably provided with means by which it may be forcibly withdrawn from a casting and to 10 this end a rack bar 6 is attached to the lower end thereof, and this rack bar is engaged by a pinion 7 on a shaft 8 to the outer end of which is attached a handle 9, by means of which the shaft may be turned to raise or 15 lower the core member upwardly into molding position within the casting cavity or to remove said core member downwardly and out of the casting cavity.

The outer shell of the mold is formed by 20 two separable sections 10 and 11 which are recessed to accommodate the core member 3 between them and form the downwardly opening cup-shaped casting cavity around the core member. The sections 10 and 11 are 25 connected by extensible links 12 with arms 13 fixed to transverse shafts 14 at each end of the base or supporting member 1 rearwardly of the mold sections 16 and 17, each link 12 being shown as comprising rotatably adjustable link members oppositely threaded at 30 their ends and each connecting aligned, apertured and threaded bifurcated members pivotally secured respectively to an arm 13 and a lug extending from a mold section toward 35 one of the arms 13, the nuts directly adjacent those bifurcated members secured to the arms 13 serving to retain the link members in desired adjusted position, and nuts midway of the link members providing convenient 40 means for rotatably adjusting said link members. Each of the shafts 14 is provided with a handle 15 by which it may be turned to shift the mold sections to and from operative position. The links 12 and arms 13 form 45 toggles which are straight when the sections are in operative position in engagement with each other and which serve to hold the sections together under pressure.

The upper portions of the sections 10 and 50 11 are preferably formed of separate blocks 16 and 17 connected to the body portions of the sections by bolts 18. The inner faces of the blocks are in the planes of the inner faces of the body portions of the sections, 55 and the block 16 has fixed thereto a vertically disposed collar 19 in which is slidably mounted an auxiliary recessed core member or sleeve 20 which is movable downwardly and adapted to receive the upper end 60 of the core pin 4 and thus cooperate with the core 3 to provide an axial aperture in the casting. For lifting the sleeve 20 to free the section 10 from the core member, the rack teeth 21 are formed on the outer side thereof, 65 and these teeth are engaged by a pinion 22

formed in a shaft 23 journaled in the block 16 and provided with a handle 24 by which it may be turned to raise or lower the sleeve upwardly out of, or downwardly into, co-operative engagement with the core 3. The 70 collar 19 is fixed in a semi-cylindrical recess in the block 16 and the block 17 is provided with a semi-cylindrical recess 25 to receive the collar 19 when the sections are brought together. 75

As shown in Figs. 5 and 6, the casting formed in the mold has a cylindrical skirt portion 26 and a top portion 27 which has a central opening 28 surrounded by a countersunk portion 29 and other openings 30 around the central openings. A flange 31 may be formed at the lower end of the skirt portion, and the upper portion of the casting may be reinforced by the oppositely disposed integral internal webs or bosses 32. A sprue 33 is 85 joined at its lower end to the skirt portion 26 by a straight narrow elongated web 34, which extends from the upper end of the skirt toward the bottom in a direction parallel with the axis of the casting. A riser 35 90 diametrically opposite the sprue 33 is joined at its lower end to the skirt portion 26 at the upper end thereof by a narrow web 36 parallel with the web 34 which is shown as but considerably shorter than the web 34. 95

The mold sections 10 and 11 are identical except for the fact that the collar 19 and auxiliary core member or sleeve 20 are carried by the section 10. When in engagement the sections 10 and 11 abut in a vertical plane 100 including the axis of the core member 3, and are provided with complementary recesses corresponding to halves of the casting on opposite sides of an axial plane passing centrally through the sprue and riser. The opposed 105 faces of the sections, therefore, have recesses, each corresponding to one half of the casting cavity, and on opposite sides of these recesses other recesses corresponding to one half of the sprue and one half of the riser cavity, 110 the deeper portions of the gate and riser recesses being connected to the mold cavity forming recesses by wide shallow grooves 115 which are substantially vertical in longitudinal extent and which, when brought together 120 form the long, narrow gate cavities opening from the gate and riser cavity into substantially vertical portions of the mold cavity. The sections 10 and 11 have shouldered portions 37 which fit over the upper end of the 125 sleeve 2. The shoulder 37 may be spaced above the top of the sleeve 2 to form the flange 31 of the casting. When the mold is assembled for casting, the sleeve 20 projects slightly into the casting cavity to form the 130 countersunk portion 29, and the projections 5 of the core member engage the sections 10 and 11 of the top of the casting cavity.

To position the parts of the mold for casting, the core member 3 is raised to its upper- 135

most position by turning the handle 9, the sections 10 and 11 are brought together by turning the handles 15, and the sleeve 20 is lowered onto the pin 4 by turning the handle 24. The molten metal is poured into the sprue cavity and flows through the gate cavity to all parts of the casting cavity uniformly to form sound castings and into the riser cavity, air being thus permitted readily to escape from the casting cavity. The metal of the casting shrinks during cooling and draws additional metal both from the sprue and from the riser, molten metal being thus provided to feed the boss portions. After the casting has hardened sufficiently, the sleeve 20 is raised clear of the casting, the sections 10 and 11 are moved away from the casting and the core member 3 is lowered out of the casting, after which the casting can be taken away.

It will be noted that the toggle means shown in the drawings for moving the mold sections into and maintaining the mold sections in molding position are simple and efficient. Moreover, by reason of the links 12 being in horizontal position when the mold is closed, the mold sections are positively locked in molding position. The extensibility of the links 12 furthermore provides a means of adjustment whereby the mold sections may always be brought into desired closely engaging position although warpage or expansion of the mold sections, for example, has taken place.

It will also be seen that I have provided an advantageous structure for forming axial apertures in a cup-shaped casting. Thus, the recessed auxiliary core member 20 carried by the mold section 10 is arranged to be moved downwardly to receive the upwardly extending core pin 4 carried by the core 3.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

What I claim is:

1. In a permanent mold adapted for casting substantially cup-shaped articles from aluminum alloys and the like, in combination, a support, a plurality of separable mold sections, means for guiding said mold sections into and out of molding position on said support, said mold sections having complementary recesses in their inner faces forming a substantially cup-shaped casting cavity opening downwardly, a permanent core arranged to be moved upwardly into molding position within said casting cavity and to be withdrawn downwardly therefrom, and an auxiliary core member carried by one of said mold sections and movable downwardly into co-

operative engagement with said core whereby an axial aperture may be formed in the casting.

2. In a permanent mold adapted for casting substantially cup-shaped articles from aluminum alloys and the like, in combination, a support, a plurality of separable mold sections, means for guiding said mold sections into and out of molding position on said support, said mold sections having complementary recesses in their inner faces forming a substantially cup-shaped casting cavity opening downwardly and a sprue cavity and a relatively narrow gate intermediate and communicating with said sprue and casting cavities, a permanent core arranged to be moved upwardly into molding position within said casting cavity and to be withdrawn downwardly therefrom, said core carrying a core pin extending upwardly therefrom, an auxiliary recessed core member carried by one of said mold sections and movable downwardly to receive said core pin whereby an axial aperture may be formed in the casting.

3. In a permanent mold, in combination, a support, a mold section carried by said support, and means for moving said mold section into desired position relative to another mold section, said means comprising a rotatable shaft carried by said support and disposed rearwardly of said mold section and transversely of the direction of movement thereof, a pair of spaced arms carried by said shaft, a pair of spaced lugs carried by said mold section each extending toward said transverse shaft in substantial alignment with one of said arms, bifurcated members pivotally secured to each said lug and arm, each bifurcated member having a longitudinal aperture threaded to cooperate with a link member, link members each oppositely threaded at its ends and connecting aligned bifurcated members secured to a lug and an arm, means whereby said link members may be rotatably adjusted, means for retaining said link members in desired adjusted position, and means for rotating the transverse shaft to move said mold section.

4. In a permanent mold for casting substantially cup-shaped articles from aluminum alloys and the like, a plurality of recessed separable mold sections, a permanent core arranged to be moved upwardly into molding position, said mold sections and core together defining a substantially cup-shaped casting cavity opening downwardly and arranged to form an aperture in the upper end of the casting, said mold sections being recessed to form a sprue cavity and a riser cavity, and relatively narrow gate cavities intermediate and communicating with said casting cavity and said respective sprue and riser cavities, said sprue cavity extending well above the top of said casting cavity, said sprue and riser cavities being disposed at substantially op-

posite sides of said casting cavity, said gate cavities being substantially vertical in longitudinal extent and arranged to communicate with said casting cavity at substantially vertically disposed portions thereof, whereby said casting cavity may be readily filled completely to form sound castings.

5. In a permanent mold for casting substantially cup-shaped articles from aluminum alloys and the like, a pair of recessed cooperable mold sections, a core arranged to be disposed intermediate said mold sections, said mold sections and core together defining a substantially cup-shaped casting cavity opening downwardly and having substantially oppositely disposed boss portions, said mold sections being recessed to form substantially oppositely disposed sprue and riser cavities and relatively narrow gate cavities communicating with the said sprue and riser cavities respectively and with said casting cavity adjacent said boss portions, said gate cavities being substantially vertical in longitudinal extent and arranged to communicate with said casting cavity at substantially vertically disposed portions thereof, whereby the in-

coming molten casting metal may fill the casting cavity readily and uniformly and whereby molten metal may be provided to feed said boss portions. ³⁰

6. In a permanent mold for casting substantially cup-shaped articles from aluminum alloys and the like, a plurality of recessed separable mold sections, a core arranged to be disposed intermediate said mold sections, ³⁵ said mold sections and core together defining a hollow substantially cup-shaped casting cavity opening downwardly, said mold sections being recessed to form a sprue cavity and a relatively narrow gate cavity communicating with said sprue and casting cavities, said gate cavity being substantially vertical in longitudinal extent and arranged to communicate with said casting cavity at a substantially vertically disposed portion thereof whereby the incoming molten casting metal may fill the casting cavity readily and uniformly, and whereby air within the casting cavity may readily escape therefrom. ⁴⁰ ⁴⁵

In testimony whereof I affix my signature.
